US00D824957S

(12) **United States Design Patent** (10) Patent No.: **US D824,957 S**
Seo et al. (45) Date of Patent: ** Aug. 7, 2018

(54) **DISPLAY SCREEN OR PORTION THEREOF WITH ICON**

(71) Applicant: **Samsung Electronics Co., Ltd.**, Suwon-si (KR)

(72) Inventors: **Jiu Seo**, Bucheon-si (KR); **Jinseon Jang**, Suwon-si (KR); **Hoik Hwang**, Hwaseong-si (KR)

(73) Assignee: **Samsung Electronics Co., Ltd.**, Suwon-si (KR)

(**) Term: **15 Years**

(21) Appl. No.: **29/589,585**

(22) Filed: **Jan. 3, 2017**

(30) **Foreign Application Priority Data**

Jul. 22, 2016 (KR) 30-2016-0035947

(51) **LOC (11) Cl.** **14-04**

(52) **U.S. Cl.**

USPC **D14/491**

(57) **CLAIM**

We claim the ornamental design for a display screen or portion thereof with icon, as shown and described.

DESCRIPTION

FIG. 1 is a front view of a display screen or portion thereof with icon showing our new design; and, FIG. 2 is an enlarged view of the icon as shown in FIG. 1. The broken lines in the figures illustrating the display screen or portion thereof form no part of the claimed design.

1 Claim, 2 Drawing Sheets
